[57] **CLAIM**

The ornamental design for a cabinet for electrical components, substantially as shown.

DESCRIPTION

FIG. 1 is a front elevational view of a cabinet for electrical components showing our new design;

FIG. 2 is a side elevational view thereof, the opposite side being a mirror image;

FIG. 3 is a top, front and side perspective view thereof; and

FIG. 4 is a front elevational view of a second embodiment of a cabinet for electrical components, the undisclosed sides being identical to FIG. 2.

The undisclosed rear is flat and unornamented.

FIG. 1

FIG. 3

FIG. 2

FIG. 4
